CLAIM

The ornamental design for a cat house, as shown and described.

DESCRIPTION

FIG. 1 is a perspective view of an ornamental design for a cat house, as viewed from the front, left, and top.

FIG. 2 is a front view of the cat house of FIG. 1.

FIG. 3 is a rear view of the cat house of FIG. 1.

FIG. 4 is a right view of the cat house of FIG. 1.

FIG. 5 is a left view of the cat house of FIG. 1.

FIG. 6 is a top view of the cat house of FIG. 1; and,

FIG. 7 is a bottom view of the cat house of FIG. 1.

In FIGS. 1-7, broken lines represent environmental structure that forms no part of the design to be patented.

The claimed design shows a contrast of materials by using line shading in one area and stippling in another.
